AXMINSTER LOOM

William W. Robertson, Worcester, Mass., assignor
to Crompton & Knowles Loom Works, Worcester, Mass., a corporation of Massachusetts

Application October 24, 1932, Serial No. 639,257
Renewed February 9, 1934

3 Claims. (Cl. 139—8)

This invention relates to looms in which a pile or tufted fabric may be produced, with the pattern clearly appearing on the back of the fabric. Such a loom is shown and described in the prior application of Dacey and Robertson, Serial No. 575,190, filed November 16, 1931.

It is the general object of my present invention to improve the mechanism shown in said prior application, in which I am a joint inventor.

10 An important feature of my present invention relates to improvements by which the guide-plates described in said prior application are caused to more closely engage the reed dents at a certain point in the loom cycle, resulting in more effective 15 yarn guidance.

In the preferred form, the guide-plates are caused to directly abut the reed dents, and are held for a predetermined period in yielding engagement therewith.

20 My invention further relates to arrangements and combinations of parts which will be herein-after described and more particularly pointed out in the appended claims.

A preferred form of the invention is shown in 25 the drawings, in which

Fig. 1 is a sectional side elevation showing parts of a loom embodying my improvements;

Fig. 2 is a sectional side elevation showing the 30 spacer, reed dents and guide-plates on an enlarged scale;

Fig. 3 is a detail front elevation of certain parts, looking in the direction of the arrow 3 in Fig. 2;

Fig. 4 is a detail plan view, looking in the direction of the arrow 4 in Fig. 3;

35 Fig. 5 is an enlarged side elevation of a portion of the actuating cam which moves the guide-plates;

Fig. 6 is an edge view of the cam, looking in the direction of the arrow 6 in Fig. 5;

40 Fig. 7 is a detail sectional elevation, taken along the line 7—7 in Fig. 5, and

Figs. 8 to 13 are diagrammatic views showing the operation of the parts in forming a yarn loop and tuft.

45 Referring particularly to Figs. 1 to 4, I have shown portions of a loom which is in general of a usual Axminster type and comprises a frame 20, a breast beam 21, and a lay 22 mounted on arms 23 secured to a cross shaft 24 and oscillated by a 50 cam (not shown) which acts through a cam lever 25.

A plurality of reed dents 26 are mounted on the lay 23 and are secured thereto in predetermined spaced relation by a lock plate 27 and a slotted 55 spacer bar 28. The usual yarn tubes T are trans-

ported by a pattern chain C and are removed from the chain and presented to the fabric B by the usual arms or levers 30 which are actuated in the manner customary in this type of Axminster looms. Yarn tubes Y on the tube frames T are 30 so spaced that they will dip between adjacent reed dents 26 during the insertion of the yarn ends and the formation of the pile loops.

Front and rear pile-cutting knives 31 and 32 are mounted on knife-bars 33 and 34 and these 35 parts are actuated at predetermined times in the usual manner to sever the tuft yarn ends after a row of yarn loops has been formed in the fabric. Binder warps W are drawn from warp beams or other usual sources of supply and pass between 70 the reed dents 26 on the lay 22.

A spacer or nose bar 40 is mounted in fixed position in the loom frame 20 and extends across the loom in front of the reed dents 26. Parallel teeth 41 extend rearward from the nose bar 40 into 75 the spaces between the reed dents 26 and are provided at their rear ends with inclined rear surfaces 42 and hook-shaped projections 43. As shown in Fig. 4, the spaces between adjacent teeth 41 are wide enough to receive the dents 26 80 and also to provide clearance for the binder warp threads W.

In addition to the reed dents 26 and teeth 41, there is also provided a movable cross bar 45 having a plurality of spaced parallel guide plates 85 46, aligned with the reed dents 26 and adapted to enter between the fixed teeth 41 as indicated in Figs. 3 and 4.

The cross bar 45 is mounted on supports 47 secured to the forwardly extending ends of arms 90 48, which arms in turn are mounted on a cross shaft 49 supported in fixed bearings in the loom frame 20. Consequently the cross bar 45 and guide plates 46 swing about the axis of the shaft 49 as a pivot.

95 Lifter rods 50 are connected at their upper ends to the cross bar 45 and at their lower ends to arms 51 mounted on a supporting shaft 52 (Fig. 1) having a depending actuating arm 53. This actuating arm is connected by a link 54 and 100 give-way device 55 to a stud 56 in the upper end of a lever 57.

A cam roll 58 on the lever 57 is engaged by an actuating cam 60 on the usual bottom or cam shaft 61 of the loom. The cam 60 is preferably 105 of special construction and comprises a circular disc having a cam plate 62 secured thereto at one point in its periphery. A contact member 63 (Figs. 5 to 7) is pivoted at 64 to the cam plate 62 and is engaged at its lower end (as viewed in 110

Fig. 5) by a stop screw 65 mounted in a projection 66 of the cam plate 62.

A spring 67 is seated in a pocket 68 (Fig. 7) of the cam plate 62 and yieldingly supports the upper end of the contact member 63, as indicated in Fig. 5. The upper end portion of the contact member 63 is closely adjacent to an abrupt shoulder 69 on the cam plate 62, and is in substantial alignment with the outer edge of the cam plate 10 but may be yieldingly depressed as will be herein-after described.

The outer edge surface 70 (Fig. 1) of the cam plate 62 is preferably substantially concentric with the shaft 61 but with a wavy or irregular 15 outline, also for a purpose to be described.

Having described the details of my invention and its application to a loom of the type shown in the prior Dacey and Robertson application, the method of operation of the loom and improvements 20 may be briefly described as follows, reference being made to Figs. 8 to 13:—

In Fig. 8 the parts are shown with the guide-plates 46 in forward position and the reed dents 26 moved partially forward from the extreme rear 25 position indicated in dotted lines, which rear position the dents 26 occupy during the insertion of the first filling pick F.

The reed dents 26 are moved further forward 30 until the filling F substantially engages the inclined rear faces 42 of the fixed teeth 41. The binder warps W are then crossed to hold the filling F in this forward position, and the reed dents 26 move rearwardly to the position shown in Fig. 9, while the yarn tubes Y simultaneously descend 35 between the warps W and also between the guide plates 46, which guide plates have simultaneously begun their rearward movement.

This movement of the guide plates 46, combined 40 with the rocking movement of the tube frame T and yarn tubes Y, causes the yarn ends E to be wiped between the guide plates 46, as indicated in broken and dotted lines in Fig. 9.

During this wiping-in of the yarn ends E, the wavy outline of the portion 70 of the cam plate 45 62 causes the guide plates 46 to receive a vibrating or oscillating movement while in general rearward position, as indicated by full and broken lines in Fig. 9.

The second pick F² of filling is then inserted 50 as indicated in Fig. 10 and the reed dents 26 move forward to beat up the second pick F². As the reed dents 26 continue their forward movement, the adjacent edges of the reed dents 26 and guide plates 46 engage each other, as indicated in Fig. 55 11, thus forming substantially continuous aisles for the yarn ends Y, preparatory to the loop-forming operation indicated in Fig. 12.

The reed dents 26 continue their forward 60 movement to force the filling picks F' and F² up the inclined faces 42 and over the hooks 43, while at the same time the guide plates 46 move forward toward initial position.

The reed dents 26 again move rearwardly to 65 permit insertion of the third filling pick F³, which is thereafter beaten up by the reed dents 26. The knives 31 and 32 are operated to sever the yarn ends which form the pile, and the tuft-forming cycle is then complete.

For a more detailed and complete description 70 of the loom operation, reference is made to the prior application above identified.

The advantages of my present improvement reside largely in the provision of the yielding

contact member 63 on the cam plate 62, by which yielding member the guide plates 46 and reed dents 26 are held in firm but yielding contact when in the position indicated in Fig. 11. This insures a continuous aisle or passage between the parts 46 and 26, while at the same time avoiding the possibility of injury which might result if these parts were both moved positively to abutting position. By the use of the yielding contact member 63, abutting contact of the parts 46 and 26 may be readily achieved and may be maintained for a desired time interval.

Furthermore, the provision of the give-way device 55 in the connections between the cam 60 and the cross bar 45 permits the actuating lever 57 to be entirely disconnected if any displacement of parts interferes with the usual operative movement of the guide plates 46.

My improvements thus permit the machine to 95 be operated more safely and also render the parts more effective in guiding the yarn ends and in preventing lateral displacement thereof.

The specific construction of the cam 60 and cam plate 62 and the method of operation thereof in oscillating the guide plates 66 is not claimed herein, as this feature is not of my invention and is described and claimed in a copending application of Edward J. Dacey, Serial No. 665,917, filed April 13, 1933.

Having thus described my invention and the advantages thereof, I do not wish to be limited to the details herein disclosed, otherwise than as set forth in the claims, but what I claim is:—

1. In an Axminster loom, a tube frame having 110 a plurality of yarn tubes from which extend yarn ends, a lay having a set of reed dents between which lie binder warps, a set of guide plates, each of which is aligned with an associated reed dent, means to move said reed dents, 115 and additional yielding means to move said guide plates, whereby said dents and plates are caused to relatively approach each other and to engage each other in yielding contact to define guide aisles for the yarn ends.

2. In an Axminster loom, a tube frame having 120 a plurality of yarn tubes from which extend yarn ends, a lay having a set of reed dents between which lie binder warps, a set of guide plates, each of which is aligned with an associated reed dent, means to move said reed dents, additional yielding means to move said guide plates, whereby said dents and plates are caused to relatively approach each other and to engage each other in yielding contact to define guide 125 aisles for the yarn ends, said additional yielding means including a cam having a yielding contact member and a cam lever actuated thereby and connected to move said guide plates.

3. In an Axminster loom, a tube frame having 130 a plurality of yarn tubes from which extend yarn ends, a lay having a set of reed dents between which lie binder warps, a set of guide plates, each of which is aligned with an associated reed dent, means to move said reed dents, additional means to move said guide-plates, whereby said dents and plates are caused to relatively approach each other and to engage each other to define guide aisles for the yarn ends, and a give-way connection between said additional 135 means and said guide plates.

WILLIAM W. ROBERTSON.
